UNITED STATES PATENT OFFICE.

DANIEL GRIFFITH, OF GIDDINGS, TEXAS.

DESIGN FOR A KITCHEN-CABINET.

48,635.

Specification for Design.

Patented Feb. 29, 1916.

Application filed June 12, 1915. Serial No. 33,828. Term of patent 14 years.

To all whom it may concern:

Be it known that I, DANIEL GRIFFITH, a citizen of the United States, residing at Giddings, county of Lee, and State of Texas, have invented a new, original, and ornamental Design for Kitchen-Cabinets, of which the following is a specification, reference being had to the accompanying drawing, forming part thereof.

The accompanying drawing is a view of

a kitchen-cabinet in front elevation showing my new design.

I claim:

The ornamental design for a kitchen-cabinet, as shown.

DANIEL GRIFFITH.

Witnesses:

SALLIE B. TRUSDEL,
JNO. H. JENKINS.
